UNITED STATES PATENT OFFICE.

WILLIAM M. LEVERING, OF PHILADELPHIA, PENNSYLVANIA.

CABLE RAILWAY.

SPECIFICATION forming part of Letters Patent No. 315,800, dated April 14, 1885.

Application filed February 3, 1885. (No model.)

To all whom it may concern:

Be it known that I, WILLIAM M. LEVERING, of Philadelphia, in the county of Philadelphia and State of Pennsylvania, have invented a new and valuable Improvement in Cable Railways; and I do hereby declare that the following is a full, clear, and exact description of the construction and operation of the same, reference being had to the annexed drawings, making a part of this specification, and to the letters and figures of reference marked thereon.

My invention has relation to tubeways for cable-motor or other analogous railways; and it has for its objects to provide a frame for the conduit sufficiently strong and inflexible to prevent the slot closing at the points where the frames are attached to the slot-irons; to give the slot-irons sufficient strength between the points of support to carry any load that is liable to come upon them, and to resist the lateral pressure against them; to strongly connect the frame-work of the conduit with the rails or rail-stringers, so that said frame-work will be incapable of movement either horizontally or vertically independently of said rails to alter the distance between the slot-irons, if they should accidentally close together from any cause.

In the accompanying drawings, Figure 1 is a cross-section of the permanent way. Fig. 2 is a horizontal section through one of the frames. Fig. 3 is a side elevation of the metallic portion of the same. Figs. 4, 5, 6, 7, 8 show details of the various parts.

35 A A are solid rolled transverse ribs, bars, or sections, preferably old T-rails or deck or I beams bent in the form shown in Fig. 1, and forming a frame for the support of the slot-irons B B, such ribs or sections being placed at suitable intervals apart along the length of the roadway. The slot-irons B B are adapted to the form of the bent ribs A, the upper flanges of which slot-irons may rest on the upper ends of the bent rails A, to which said slot-irons 45 are securely bolted or riveted.

The slot-irons B B consist of a rolled section having the form of an I-beam with half a lower flange, the webs of the same having a curved section adapted to fit the form of the 50 bent ribs A.

C and C' are brackets attached to the ribs A by rivets or bolts, and at their outer extremities supporting the rail-stringers or rails, which may be attached to them by bolts or other suitable connections. The brackets C 55 and C' may be of cast or wrought metal of any suitable form, preferably of wrought-metal flanges, and may be secured to the rail stringers or to any suitable form of rail directly. The ribs A, placed at proper intervals, are connected together by bent plates of sheet metal D, riveted or bolted to the interior flange of ribs A, and forming the sides of the conduit, and the whole is supported and surrounded by the mass of concrete E, of any suitable form. The sheet-iron D may be either riveted to the slot-irons B B or be simply bent over and rest against their lower flanges.

At suitable intervals in the conduit a jack-screw, F, may be inserted between the two 70 sides of the frame, a rib, or section A, which screw has a head, G, and nut H, said head G having an extension or pin, I, (see Fig. 7,) passing through the gib K, and bearing against one side of a rib-frame, A. The gib K and 75 nut H may be notched slightly into the said ribs A, to keep them in position and prevent their turning with the nut. The bent plate L, slipped down between the head G and gib K, serves to keep the screw F from turning, 80 the notch in it fitting over the head G.

At proper intervals along the tube certain of the screws F are made to serve as axles for the cable-supporting pulleys M, which carry the moving cable, said pulleys M being mounted on the smooth cylindrical portion of the jack-screws and kept in place by the collars N. Should any of the ribs or sections A become bent and their upper ends approach each other, tending to close the grip-slot, the 90 jack-screw F may be tightened, first removing the bent plate L, so as to allow the head G to be turned, and when the slot is sufficiently opened the plate L is driven down again over the head G, locking it and preventing the 95 screw F turning from the friction of the cable or any accidental cause. A sufficient space is allowed between the head G and gib K to allow the easy entrance of the bent plate L. It is obvious that the same result may be ob- 100

tained by making the head G stationary and turning the nut H, if desired.

I do not limit myself to any particular form of frame in combination with the jack-screw F, but may apply it to any suitable form of tube, and may use any suitable form of jack-screw for the purpose.

I am aware that it has been proposed to use bent angle-iron ribs or sections extending to 10 or nearly to the upper outwardly-projecting flange of an angle-iron bar forming the slot-iron of a cable-railway conduit, and I do not claim, broadly, the support of an outwardly-turned flange of a slot-iron by its supporting-frame.

I am also aware that it has been proposed to construct a cable-railway conduit of a cast frame and wooden sides, said cast frame being connected to the tram-rail stringers by an angle-iron and knee-brace. Such is not my invention. Also, that cast-iron brackets have been proposed connecting the slot-iron directly to the tram-rail stringers, and I do not claim such bracket.

25 What I claim is—

1. Ribs or section A A for the conduit of a cable road, composed of a rolled rail, deck or "I beams" bent substantially in the form shown, and extending nearly to the surface of 30 the roadway, to the inner flange of which the slot-irons are riveted or bolted, and on the ends of which the slot-irons may rest, in combination with brackets formed of a single plate of rolled iron bent and united or bolted to the 35 frame A A, and extending to and supporting the rails or rail-stringers, substantially as described.

2. A bracket for connecting the conduit of a cable railway to the tram-rails or rail-stringers, consisting of a single plate of 40

wrought or rolled metal of nearly uniform thickness secured to the main frame of said conduit by bolting or riveting, and having suitable supports for the tram-rail or rail-stringer riveted or bolted thereto, substantially as shown.

3. A permanent way for cable railways, consisting of a rolled rail, deck or I beam, A, bent in the form substantially as shown, forming a frame, in combination with the slot-irons B B, plate D, riveted to the interior of 50 said frame, brackets C C, riveted or bolted to said frame and supporting the tram-rails or rail-stringers, and a continuous mass of concrete surrounding the same, substantially as 55 shown and described.

4. In combination with a cable-motor or other slotted conduit, jack-screws F, forming an integral part of the permanent construction, as and for the purpose set forth. 60

5. In a cable or other slotted conduit, the jack-screw F, forming a bearing or support for a cable-supporting pulley, and devices for preventing said jack-screw in position and preventing its rotation, substantially as shown 65 and described.

6. A slot-iron for cable railways substantially of the form shown, having a general shape of an I-beam or T-beam with half a lower flange, with the flanges at an obtuse 70 angle with the web, said web being rolled in a curved form to fit the bend in the rail forming the frame.

In testimony that I claim the above I have hereunto subscribed my name in the presence 75 of two witnesses.

WILLIAM M. LEVERING.
